UNITED STATES PATENT OFFICE

MAX NATHAN AND ARTHUR GROSS, OF NEW YORK, N. Y.

DESIGN FOR A MOURNING RING

Application filed March 5, 1932. Serial No. 43,103. Term of patent 14 years.

To all whom it may concern:

Be it known that we, MAX NATHAN, a citizen of the United States, residing at New York city, in the county and State of New York, and Arthur Gross, a citizen of the United States, residing at New York city, county of Bronx, State of New York, have invented a new, original, and ornamental Design for a Mourning Ring, of which the following is a specification, reference being had to the accompanying drawing forming part thereof.

The figure on the drawing is a perspective view of a mourning ring showing the design thereof which is repeated at intervals around the ring.

We claim:

The ornamental design for a mourning ring as shown and described.

In testimony whereof, we affix our signatures.

MAX NATHAN.
ARTHUR GROSS.
